ORE REDUCING MACHINE

Alvah D. Hadsel, Oakland, Calif.

Application October 14, 1933, Serial No. 693,659

5 Claims. (Cl. 83—46)

The present invention relates to improvements in ore reducing machines and its general object is to provide a machine of the revolving type in which ore may be reduced expeditiously and 5 economically.

More particularly the present invention is an improvement over my invention of an ore reducing machine described in my co-pending application Serial No. 657,919, filed February 15, 10 1933. In the latter invention it was proposed to provide a drum with peripheral lifting buckets and a breaking medium so that material fed into the drum would be lifted by the buckets and dropped on the breaker medium whereby the 15 material would be comminuted. The drum was provided with flanges at opposite ends so that a certain amount of water could be retained in the drum and lighter particles dropping from the breaker medium would be made to float off 20 with the water over the edges of the drum.

In the present invention it is proposed to provide certain improvements in connection with the said machine, and more particularly it is proposed to provide means for removing certain 25 parts of the material from the drum at certain stages, to subject the removed material, exteriorly of the drum, to certain treatment for classifying the same, and to return part thereof into the drum for further impact with the impact 30 medium.

More particularly it is proposed to apply the scheme of outside treatment of certain portions of the material going through the drum in two different ways.

In the first place it is proposed to subject the material that remains in the buckets toward the end of the discharge period, which material is most apt to contain valuable particles, to separate treatment outside of the machine for removal of the valuable particles, and to return 35 the remaining material back into the drum. In the second place, it is proposed in the present invention to provide a special means for classifying light particles of material floating in the 40 upper region of the water by removing such water from the drum through an outside classifying circuit and to by then returning the water to the drum.

Further objects and advantages of my invention will appear as the specification proceeds.

The preferred form of my invention is illustrated in the accompanying drawings, in which—

Figure 1 shows a vertical transverse section through my ore reducing machine, as seen from line 1—1 of Figure 2;

Figure 2 a vertical axial section through my machine as seen from line 2—2 of Figure 1;

Figure 3 a top plan view of the machine;

Figure 4 a detail view of a removable U-shaped member supporting a breaker plate; and

Figure 5 a perspective detail view of an auxiliary bucket used in my invention.

While I have shown only the preferred form of the invention it should be understood that various changes or modifications may be made within the scope of the claims hereto attached without departing from the spirit of the invention.

In its preferred form my invention comprises a drum 1 formed with an annular series of buckets 2 which are shaped substantially in the same manner as the buckets in my co-pending application, comprising a series of vanes 3 projecting inwardly from the rim of the drum, the vanes being inclined in the direction of travel, and side flanges 4 which extend from the edges of the vanes toward the ends of the drum, in a forwardly inclined direction so that material delivered into the drum by an elevator 5 and a chute 6 first drops into the lower buckets, and is then lifted by the buckets and gradually discharged from the buckets toward the interior of the drum as the buckets rise from the horizontal center line to and beyond the vertical center line. The flanges 4 forming the sides of the buckets are inclined so as to crowd the rising material from the ends of the drum toward the intermediate section so that when the material drops from the buckets, it will be confined to a central zone of the drum intermediate the two ends thereof. The drum is provided with flanges 7 and 8 at opposite ends so that a certain amount of water may be accommodated in the drum, the water being fed into the drum through a suitable pipe 9.

The drum according to the present invention is supported externally on a semi-circular series of rollers 10 and rotary motion is imparted to the drum in any suitable manner through a chain 11 and a motor indicated at 12. At the opposite ends of the drum I provide standards 13 preferably made of concrete, and these standards support two I-beams 14 which extend transversely through the entire drum, and which support two substantially semi-circular baffle plates 15 within the drum in spaced relation to one another so that all the material dropping from the buckets 2 is confined to a central zone between the two baffle plates. The baffle plates serve as supporting means for a series of sub-

stantially U-shaped elements 16, one of which is shown in Figure 4, and which are adapted to hook over the baffle plates as shown at 17, and to be arranged in adjacent relation as shown in Figure 1. These U-shaped members are provided in the bottoms thereof with breaker plates 18 and the two end members receive additional support on the I-beams 14 while the three inner members are suitably supported on angle clips 19 secured to the opposing baffle plates respectively. It will be noted that the I-beams and all the breaker plates are arranged at a slight angle to the horizontal plane, the angle being such that the dropping material which follows 15 a curved path strikes the breaker plates substantially at right angles. It should also be noted that two series of breaker plates are provided, an upper series and a lower series, the breaker plates of the lower series being arranged 20 in staggered relation to those of the upper series.

The device thus far described is substantially similar, except for certain structural features, to the device described in my co-pending application. In distinction from the co-pending application I provide means for guiding certain portions of the material to the outside of the drum for separate treatment.

One of these means is intended for special treatment of concentrates contained in the ore. 30 As the ore is raised in the buckets, the heavier particles or concentrates have a tendency to gravitate toward the bottom of each bucket, and the particles of lighter specific gravity are crowded toward the top of the layer accommodated in each bucket. The lighter particles will therefore be discharged first while the heavier particles or concentrates, due to their greater inertia, will remain in the buckets toward the last. As the buckets, for instance, rise above 35 the horizontal center line, the top layer of each bucket containing the lighter weight material will roll off first, and will be discharged upon the breaker plates. This process will substantially continue until the buckets reach the vertical center line, at which time most of the material has been discharged from the bucket, and only a thin layer of very heavy material such as 40 concentrates remains in the bucket. It is my intention to catch these heavy concentrates remaining in the buckets toward the last for separate treatment, and for this purpose I provide a trough 20 which extends into the drum at the place indicated, that is substantially in a position where it will catch the last remnants of material dropping from the buckets. This trough 45 is covered by a wire screen 21 which will allow only the finer material to pass into the trough while the coarser material is discharged into the drum and follows the course of the material. The trough 20 is inclined downwardly so as to 50 carry the fine concentrates which pass through the screen toward the outside of the drum and to discharge the same upon a suitable concentrating device such as the sluice box 22 indicated diagrammatically in Figure 1. This sluice box or 55 other concentrating or classifying device retains the precious particles of the concentrates and discharges the remainder into a second trough 23, which extends into the drum and returns the material rejected by the sluice box back into 60 the circuit of the bulk of the material. In this manner the precious metal or a large portion thereof is automatically taken out of the circuit and is separated in an external circuit.

75 I further provide a means for classifying the

lighter particles which float in the water contained in the drum. It will be understood that as the material is discharged from the buckets 5 it drops on the breaker plates, is comminuted in part and the broken particles are returned from the breaker plates through the water toward the bottom of the drum. During this process the lighter particles are arrested on or near the surface of the water and the object of my second improvement is to catch these lighter 10 particles, and to subject the same to an independent process of classification outside of the general circuit of the drum. For this purpose I provide an annular series of buckets 24 somewhat similar in shape to the main buckets, but 15 arranged closer to the axial center of the drum and at one or both ends of the drum so as to offer no interference to the operation of the main buckets. These small buckets, several of which are shown in detail in Figure 5, are arranged to skim the surface of the water contained in the drum and to catch the lighter particles floating in the water, to raise the water containing the lighter particles, and to drop the same on a trough 25, which is inclined to carry 20 the water outside of the drum and into a suitable classifying device indicated diagrammatically at 26. From the classifying device the water returns through a trough 27 into the drum for further coaction with the other material contained 25 in the main drum.

It will thus be seen that due to my two improvements the concentrates are gradually worked out of the main circuit, and treated in a separate circuit outside of the drum, while on the other hand the fines are also separately treated and classified outside of the main drum. Any overflow passing the edges of the drum may be accommodated in suitable launders 28.

The operation of the device will be readily understood from the foregoing description. Material is fed into the drum through the chute 6 and passes through the water confined in the drum to the lower buckets. The latter raise the material and gradually discharge the same for 40 violent impact with the breaker plates whereby the material is comminuted and made to gravitate from the breaker plates back to the lower buckets. In passing the lighter particles are arrested and are picked up by the secondary buckets skimming the surface of the water and are 45 discharged on the trough 25, and subjected to classification in the device 26, a part of the water and such particles as are rejected by the classification device being returned into the general 50 circuit through the trough 27.

While the bulk of each bucket is made to drop on the breaker plates, a small portion of the heavy concentrates which remain in the buckets toward the last are dropped on the trough 20 and are passed over the sluice box or other concentrating device 22 from where rejected material 60 is passed back into the circuit of the main drum over the trough 23.

Special attention is called to the supporting 65 means for the drum including the rollers 10. These rollers are made to form projecting parts of a chain 30 suspended from the spaced standards 31 with sufficient slack to adjust itself to the circumference of the drum. The chain comprises a plurality of links 32 pivotally secured to shafts 33 on which the rollers 10 are free to revolve, the rollers being held against inward movement on the shafts by collars 34. Short brackets 35 hold the lower portion of the chain 70 75

against sidesway. The rollers thus supported will automatically adjust themselves to unevenness in the surface of the drum so that all rollers bear an even share of the load.

5 I claim:

1. In combination, a breaker medium, a drum having buckets for elevating material and for gradually dropping the same over a length of period on the breaker medium in a continuous

10 circuit, a trough extending into the drum lengthwise and having a screen covering the same and being positioned to catch material remaining in the buckets toward the end of the discharge period and being inclined to carry the material outside of the drum, a classifying means adapted to receive the material from the trough and a second trough disposed to receive material discharging from the classifying means and to return the same to the inside of the drum.

15 2. In combination, a breaker medium, a drum for holding water and material, buckets on the periphery of said drum for elevating material and for dropping the same on the breaker medium in a continuous circuit, the breaker medium being shaped to cause material to gravitate therefrom through the water to the buckets at the bottom of the drum, and a second series of buckets arranged in the drum on a smaller radius so as to skim the water and catch material floating near the top of the water for separate classification of the latter material.

20 3. In combination, a breaker medium, a drum for holding water and material, buckets on the periphery of said drum for elevating material and for dropping the same on the breaker medium in a continuous circuit, the breaker medium being shaped to cause material to gravitate therefrom through the water to the buckets at the bottom of the drum, a second series of buckets arranged in the drum on a smaller radius so as to skim the water and catch material floating

near the top of the water and to raise the same for dropping, a trough mounted for receiving the said material and for guiding the same outside of the drum, a classifying means for receiving the said material from the trough and a second trough having communication with the classifying means and adapted to return the water to the drum.

25 4. In an ore reducing machine, a circular row of buckets for elevating material and then for letting it fall, means for catching only the material last to leave the buckets during the dumping period, means for classifying the caught material, and means for returning the portion of the classified material not wanted back into the buckets, and screening means disposed over the material catching means for preventing material larger than a predetermined size from being caught and classified.

30 5. In an ore reducing machine, a breaker medium, a drum enclosing the breaker medium and having buckets on its inner periphery for elevating material and for dropping the same on the breaker medium in a continuous closed circuit, the bottoms of the buckets being so inclined when they reach the top of the drum that they will drop the material over the same area for each rotation of the drum, the inclined bucket bottoms causing the concentrates of the material to leave the buckets after the buckets have passed the top center of the drum, means placed at the top of the drum and beyond its vertical center line in the direction of rotation for receiving the concentrates as they leave the buckets, screening means associated with said concentrate receiving means for permitting concentrates up to a predetermined size to enter said means, and means for classifying the separated concentrates by weight and for returning the lighter concentrates back into the circuit.
